BARBECUE CADDIE

Robert A. Clark, Allentown, Pa., assignor to Caloric Corporation, Topton, Pa., a corporation of Pennsylvania

Filed Oct. 15, 1965, Ser. No. 87,512

Term of patent 14 years

(Cl. D81—10)

FIG. 1 is a top plan view of a barbecue caddie embodying the design.

FIGS. 2, 3, and 4, are elevational views showing the three sides of the barbecue caddie, the bottom of which is plain.

I claim:

The ornamental design for a barbecue caddie, as shown and described.
